UNITED STATES PATENT OFFICE

RICHARD F. SCHULZKE, OF PORTLAND, OREGON

STEPLADDER

Application filed June 24, 1929. Serial No. 373,276.

This invention relates to improvements in step-ladders.

The primary object of this invention is the provision of a step-ladder of the type including a main ladder portion and a pivoted supporting frame, and having associated therewith an improved automatic spread and locking device which is of a fool-proof nature that will readily permit the main ladder body and pivoted supporting frame to spread apart, and automatically lock these parts in their spread relation in safety; the automatic spread and locking device being of a type which may be safely manually handled to avoid pinching of fingers.

A further object of this invention is the provision of an improved bucket or article supporting shelf construction, cooperating in a novel relation with the locking device so as to be accurately positioned in an extended braced relation upon the spread of the parts of the latter to the degree where the locking device locks them in such spread relation.

Other objects and advantages of this invention will be apparent during the course of the following detailed description.

In the accompanying drawings, forming a part of this specification, and wherein similar reference characters designate corresponding parts throughout the several views:

Figure 1 is a sectional view taken vertically through the step-ladder, with the parts thereof in extended position for use.

Figure 2 is a similar sectional view with the parts folded in a compact relationship.

Figure 3 is a rear elevation, partly in section, of the ladder with the parts folded.

Figures 4 and 5 are sectional views taken substantially on their respective lines in Figure 1 of the drawings.

In the accompanying drawings, wherein for the purpose of illustration is shown only a preferred embodiment of this invention, the letter A may generally designate the improved step-ladder, which may comprise a main ladder body B having a pivoted supporting frame C associated therewith; the parts B and C having an automatic spread and locking device D and a bucket or article

supporting shelf construction E collapsibly associated therewith.

The main ladder body A preferably includes the uprights 10 and 11, connected conventionally by the transverse steps 12 in any approved relation. At the top of the standards 10 and 11 there is provided the usual top step or platform 14, in a rigid relation with said uprights or standards 10 and 11. Pressed steel brackets 17 are connected to the standards 10 and 11, at the outer sides thereof, beneath the platform 14, having extensions to which the pivoted supporting frame C is pivoted, as at 20.

The pivoted supporting frame C preferably comprises legs 21 and 22, which at their upper ends are pivoted as above described, at 20, to the brackets 17. In the plane of the legs 21, and therebetween, at the lower portion of said frame, there are provided metal diagonal cross braces, of a construction best shown in Figures 1 and 3 of the drawings. This cross brace construction preferably comprises substantially V-shaped metal brace bars 24 and 25, the apices of which are flattened off, and adapted to lie in abutment, and be riveted together as shown at 26, along the longitudinal center line of the ladder. The divergent legs 28 of the V-shaped metal bars 24 and 25 are flanged at 29, the ends 29 thereof, and riveted as at 30 to the inner sides of the legs 21 and 22 of the pivoted supporting frame C, as shown in Figure 3. This arrangement of the metal reinforcement between the legs 21 and 22 is in effect a pair of diagonal braces. The lowermost ends of said bracket pieces 24 and 25, where they are secured on the legs 21 and 22, cooperate with the upturned ends of a transverse brace 33 which extends substantially normal to the legs 21 and 22 for the purpose of bracing the latter; said upturned ends being secured at 29 also to the legs 21 and 22.

The bucket or article supporting shelf construction preferably comprises a shelf body 40 connected between supporting arms 41 and 42; the arms 41 and 42 being riveted in a rigid relation at opposite side edges of the body 40, ends of the bracket arms 41 and 42

extending rearwardly and being pivoted as at 43 intermediate their ends to the legs 21 and 22 respectively of the supporting frame C of the ladder. The rivets 43 are located between the front and rear edges of the legs 21 and 22 of the pivoted supporting frame, and the bracket arms 41 and 42 lie along the inner sides of said legs 21 and 22 respectively. The construction E furthermore includes connecting links 44 and 45 pivoted at 46, at the ends of the shelf supporting bracket arms 41 at the opposite sides of the pivots 43 from the shelf 40; said connecting links being pivoted as at 47 to the legs 10 and 11 of the main ladder body B, at the inner sides of said legs 10 and 11. The relation of the bracket arms 41 and 42, the connecting links 44 and 45, and the pivot connections 43, 46 and 47 is such that when the ladder body B and the pivoted supporting frame C are spread the maximum extent, as permitted by the automatic spread and locking device D, the supporting shelf body portion 40 will lie horizontal, with the supporting brackets 41 and 42 horizontally positioned, and the connecting links 44 and 45 diagonally extending upward from the pivot connections 46 to the pivot connections 47, so that the thrust incident to support of articles on the shelf 40 will be efficiently transmitted through the connecting links to the legs of the ladder body B, without undue strain on any of the parts of the article supporting construction E, and permitting the same to function without buckling or inefficient placement of parts. The parts of the construction E, due to their arrangement, assume the position shown in Figure 1 when the ladder body B and its supporting frame C are spread to the maximum extent as permitted by the device D. The links 44 and 45 are provided with stop extensions 44a for abutment with the ends of the bars 41 and 42, to limit the extended movement of the device E.

Referring to the automatic spread and locking device D, the same comprises a bale-shaped device 50, best shown in Figure 4 of the drawings, including the legs 51 and 52, the ends of which are flattened and pivoted at 53 to bracket clips 54 and 55; the latter being secured at 57 to the legs 10 and 11 respectively of the ladder body B, at the inside of said legs, as shown in Figures 1 and 4. The clips 54 are of course rigidly positioned upon the legs 10 and 11, and the legs 51 and 52 converge toward their free ends, whereat U-shaped loops 60 and 61 are respectively provided, outturned from each other and transverse to the axes of said legs; the same providing openings 62 and 63 in facing relation. The extreme ends of the metal bars forming the legs 51 and 52, as shown at 68 and 69, are inturned in axially aligning relation, and rotatably receive thereon a wooden

handle 70 of substantially cylindrical formation.

Guide bars 65 and 66 are secured at their ends to the inner sides of the legs 21 and 22 of the pivoted supporting frame C; said guide bars being rigidly riveted at their ends and lying in spaced relation from their respective legs 21 and 22, and being threaded thru the openings 62 and 63 respectively to guide the bale device 50 in its movement, at the free end, along the pivoted supporting frame, to permit the collapsing of the parts B and C of the latter, in a manner which is obvious from the foregoing.

In the operative positioning of the automatic spread and locking device D, with the parts B and C extended as shown in Figure 1, the angle between the plane of the bale device 50, and the plane in which the guide bars 65 and 66 lie is 90° or slightly less, and of course there is no liability of the free end of the bale device 50 from slipping upwardly along the guide bars 65 and 66, upon any attempted relative movement of the parts B and C of the ladder together. The bale device 50 is supported in this position at its slidable end by the lower attached ends of the guides 65 and 66. In this position the article supporting construction E will lie in the arrangement shown in Figure 1. When it is desired to collapse the parts B and C of the ladder, it is merely necessary for the operator to grasp the handle 70 and move the same upwardly slightly, to increase the angle between the plane of the guide bars and the bale device 50 to an angle of greater than 90°, and merely by pushing the parts B and C together the ladder may be collapsed.

The article supporting construction E collapses within the plane of the ladder parts, with no projections, and this is also true of the automatic spread and locking device, except for the handle 70, which projects in a relation which will permit an operator to readily grasp the same and operate it.

It is to be noted that the automatic spread and locking device D is not obstructed by other brace parts, and it is readily accessible from forwardly of the latter for operation.

Various changes in the shape, size, and arrangement of parts may be made to the form of invention herein shown and described, without departing from the spirit of the invention or the scope of the claims.

I claim:

1. In a step-ladder construction the combination of a main ladder body, a supporting frame pivoted thereto, and an article supporting shelf construction comprising a shelf having arm portions at the ends thereof pivoted between the ends upon the pivoted supporting frame and extending towards the main ladder body when the ladder is operatively positioned, and connecting links pivoted upon the main ladder body and to said

ends of the arm portions, and in such relation that when the main ladder body and pivoted supporting frame are in an operative position the article supporting shelf arms will lie in substantially a horizontal plane with
5 the connecting links extending from their pivoted connection with said arms diagonally upward to their pivot connections upon the main ladder body, and means to hold the main ladder body and pivoted supporting frames in maximum operative spread position.

2. In a step-ladder construction a main ladder body comprising standards and steps connected therebetween, a pivoted supporting frame comprising uprights pivoted at the upper end of the main ladder body, means bracing and connecting the uprights of the pivoted supporting frame, and a spread and locking device for the ladder comprising a substantially U-shaped frame including
15 spaced legs and a cross piece, the spaced legs at the ends opposite the cross piece being pivoted to the standards of the main ladder body, the U-shaped frame at the juncture of the legs with the cross piece being provided with loop eyes, and guide bars on the facing sides of
20 the uprights of the pivoted supporting frame each slidably receiving a loop eye of the U-shaped frame thereon to prevent transverse movement of the said U-shaped frame at its
25 loop eye connections with the guide bars.
